BY *W. M. Kittredge* HIS ATTY.

UNITED STATES PATENT OFFICE.

ARTHUR M. KITTREDGE, OF DAYTON, OHIO, ASSIGNOR TO THE BARNEY & SMITH CAR COMPANY, OF SAME PLACE.

DESIGN FOR A STAND FOR CAR-SEATS.

SPECIFICATION forming part of Design No. 30,957, dated June 6, 1899.

Application filed May 4, 1899. Serial No. 715,622. Term of patent 7 years.

To all whom it may concern:

Be it known that I, ARTHUR M. KITTREDGE, a citizen of the United States, residing at Dayton, in the county of Montgomery and State 5 of Ohio, have invented and produced a new and original Design for a Stand for Car-Seats, of which the following is a specification, reference being had to the accompanying drawings, forming a part thereof.

10 Figure 1 is a perspective view of the inside of the stand; Fig. 2, a front elevation of same; Fig. 3, a cross-section through the line A A of Fig. 2; Fig. 4, a vertical section through line B B of Fig. 2, and Fig. 5 a plan view of 15 the stand.

Like letters of reference indicate corresponding parts throughout the different views.

The leading or material feature of my design 20 consists in a stand for car-seats having a vertically-disposed portion *a*, which in cross-section is of the contour shown in Fig. 3 and which terminates below in an enlarged base *b*, the outline of which is shown in Fig. 3, and which base is provided with a series of 25 perforations *c* to receive screws for securing the stand to the car-floor. At the top of the

vertical portion *a* is a horizontal outwardly-projecting portion or shelf *d*, bearing the outline shown more clearly in Fig. 4, and this shelf is provided with a vertical flange *e*, having the perforations *f* and to which may be secured a wooden seat-arm of any suitable form. At the outer ends of the shelf portion *d* are the usual rail-sockets *g*. On the inside of the stand and about midway of its height 35 is a socket *h*, and from the vertical portion *a*, above the center line thereof, brackets *i* curve outwardly and upwardly to the under side of the shelf *d* to contribute strength thereto. Immediately over the sockets *g* there are 40 bosses *j*, projecting outwardly from the inside of the vertical flange *e* and forming a slot *k*.

Having described my invention, what I desire to secure by Letters Patent is—

The design for a stand for car-seats substantially as herein shown and described. 45

In witness whereof I hereunto subscribe my name this 29th day of April, A. D. 1899.

ARTHUR M. KITTREDGE.
